UNITED STATES PATENT OFFICE.

EDWARD WILLIAM MARION, OF PHILADELPHIA, PENNSYLVANIA.

MICROMETER-CALIPER.

1,098,515.

Specification of Letters Patent.

Patented June 2, 1914.

Application filed April 25, 1912. Serial No. 693,043.

To all whom it may concern:

Be it known that I, EDWARD W. MARION, a citizen of the United States, and a resident of Philadelphia, in the county of Philadelphia and State of Pennsylvania, have invented a new and Improved Micrometer-Caliper, of which the following is a full, clear, and exact description.

This invention relates to micrometer calipers, and has reference more particularly to a device of this class, which comprises a pair of relatively adjustable heads provided with measuring points, and means between the heads for altering the normal fixed distance between them.

An object of the invention is to provide an inexpensive micrometer caliper, simple, rigid and durable in construction, with which measurements from zero to any number and fractional part of standard units, as machine practice may require, can be made by a simple adjustment of the parts.

A further object of the invention is to provide a caliper of separable parts which can be clamped together so that in effect the device is of unitary construction.

The invention consists in the construction and combination of parts to be more fully described hereinafter and particularly set forth in the claims.

Reference is to be had to the accompanying drawing forming part of this specification, in which similar characters of reference indicate corresponding parts in all the views, and in which—

Figure 1 is a side elevation of my invention partly broken away and in section; Fig. 2 is a side elevation, partly in section, of a part of the caliper; Fig. 3 is a transverse section on the line 3—3 of Fig. 2; and Fig. 4 is a plan view of a part of the beam.

Before proceeding to a more detailed explanation of my invention, it should be understood that the beam of the calipers is of cylindrical form, and may be integral with the fixed head or otherwise rigidly associated with the same; also that the sections by means of which the distance between the two heads is altered may be placed on or in the beam in any desired order, and the adjustable head may be provided with any known means to keep it in alinement with the fixed head on the beam.

It is useless to say that the micrometer and the ordinary measuring point may be

interchanged without affecting the operation of the device. It will also appear from the description that my invention does not require any special adjustment while changing from one length to another. 60

Referring more particularly to the drawing, I provide a cylindrical beam 15 with two diametrically opposite keyways 16, 16. The beam has a reduced and tapered end 3, which at its extremity is provided with thread 4. On the conical end 3 of the beam a head 6 is mounted and secured in place by means of the nut 7, the head being provided at its extremity with a measuring point 8 of suitable form. Removably positioned upon the beam is a plurality of sleeves 9 of different lengths, the contacting surfaces of which are exactly ground and faced, and are perpendicular to the longitudinal axes of the sleeves. The sleeve at one end of the series abuts directly against the head 6. Bearing against the other end sleeve and adjustably carried by the beam is snugly fitted the head 10 which is provided with keys 11, received in the keyways 16, 16 of the beam 80 to prevent its turning on the beam. The head 10 is also provided at its extremity, and in alinement with the measuring point 8, with a micrometer measuring point 12 for the measurement of fractional parts of 85 a unit length.

The beam keyways 16, 16 have laterally disposed notches 17, which are spaced apart any desired lineal units for which the caliper is designed, thus permitting the clamping of the slidable head at different units of length. The clamping device consists of two threaded, cylindrical parts 18 and 19, forming a union snugly fitted on the beam. The female part 18 of the union is provided with 90 projections 20, 20 engaging in the keyways 16, 16 of the beam and registering with and engaging the notches 17 where desired. It is thus unable to rotate on the beam except to a slight degree when the projections 20 100 move into and out of the notches 17, and forms an abutment for the male part 19 of the union while clamping the head 10; the male part 19 is free to turn on the beam.

When changing from a twelve inch caliper to a length between one and two inches, the sleeves of two, three and five inches are entirely removed from the beam in the following way: The male part 19 of the union is screwed into the part 18, thus relieving the 110

- pressure on the projections 20, 20 and permitting a slight turn of the female part 18, and by so doing the projections 20, 20 engage the keyways 16, 16, and the union is 5 then removed, the washer 22, head 10 and sleeves of five, three and two inches following, the inch sleeve remaining on the beam against the fixed head. Then the head 10, washer 22 and the union is mounted again 10 on the beam in order as described, and all is clamped by simply engaging in the proper notches the projections 20, 20 of the part 18 and unscrewing the part 19 bearing against the washer 22.
- 15 It can be easily seen that by proper combination of the four sleeves of one, two, three and five inches, any measurement between zero and twelve inches may be made, the measuring points of the heads 6 and 10 being 20 one inch apart when their lower tubular portions are in engagement, with all of the sleeves removed. The sleeves themselves may be verified on the device described for exactness of their lengths.
- 25 Having thus described my invention, I claim as new, and desire to secure by Letters Patent:—
1. The combination as described comprising a beam, two heads provided with measuring points, means between said heads for adjustably spacing them apart, a clamping device on said beam consisting of engaging threaded parts, and means associated with said clamping device and said beam to hold 30 all parts of the caliper in unitary relation at a desired point on said beam.
2. The combination as described, comprising a beam, two heads on the beam, one of which is adjustable, means between said 35 heads for adjustably spacing them apart, a two-part clamping device for the adjustable head, the parts of which are threadedly engageable, and coöperating means carried by one of said clamp parts and said beam 40 whereby the former may be locked against

longitudinal movement with respect to the latter, at a plurality of points thereon.

3. The combination as described, comprising a beam, having opposite longitudinal slots, two heads on the beam, one of which 50 has members extending into the beam slots whereby to prevent its rotation with respect to the beam, and at the same time permit of its longitudinal adjustment, independently removable spacing rings disposed on 55 the beam between the said heads, a clamping device on the beam for the said adjustable head and comprising two members threadedly coupled to one another, one of said members being provided with inwardly extending projections movable in the said beam slots, and said beam being also provided with a plurality of notches alongside its slots, into selected ones of which the said projections may be moved whereby to lock 60 one of the clamped members against movement.

4. The combination of a beam, a fixed head and a slidable head on the beam, measuring points on the said heads, a plurality 70 of tubular sections of different lengths movably mounted on the beam between the said heads and in close contact with each other and with the heads whereby to vary the distance between the said heads, a member 75 adapted to follow the movable head on the beam and having means whereby to adjustably engage the latter at a plurality of points therealong, and a member abutting said first named member and adjustable between the latter and the said slidable head 80 to clamp the head against one of the tubular sections.

In testimony whereof I have signed my name to this specification in the presence of 85 two subscribing witnesses.

EDWARD WILLIAM MARION.
